STOOL

Raymond A. Wagner, Sr., Quakertown, Pa.

Application January 12, 1943, Serial No. 472,148

1 Claim. (Cl. 155—196)

My invention relates to a new and useful stool or article of furniture and the construction employed for attaching the legs to the seat and the arrangement of connecting the stretchers to the legs for bracing the entire structure.

An object of the present invention is to provide a stool that can be made entirely of wood and thereby eliminate the use of metal which is exceedingly scarce at present.

Another object of this invention is to construct a stool including a seat having dovetail sockets to receive the dovetail tenons of several legs which latter are braced and tied together in pairs by stretchers having dovetail tenons at their ends for insertion in dovetail notches in the legs.

A further object of the invention is to form an individual dovetail socket for each leg in the underneath face of the stool seat, each of said sockets comprising a dovetail recess or cavity and an ante-chamber leading to and communicating with its associated recess or cavity at one end thereof.

Where nails, screws or dowels are used in the construction of stools of this character it has been discovered that due to shrinkage, the stresses resulting from usage or other causes, the attaching means soon become loose and the legs or other parts become detached making the whole structure useless. Therefore a still further object of the invention is to provide a stool that is strong and durable yet simple in construction and easily and quickly assembled in the course of manufacture.

With the above and other objects in view this invention consists of the details of construction and combination of elements hereinafter described and then designated by the claim.

In order that those skilled in the art to which this invention appertains may understand how to make and use the same, I will describe its construction in detail, referring by numerals to the accompanying drawing, in which—

Fig. 1 is an elevation of a stool made in accordance with my invention, the near side leg being partially broken away to illustrate details of construction.

Fig. 2 is a perspective view of one of the legs.

Fig. 3 is a fragmentary perspective view of one of the stretchers.

Fig. 4 is a horizontal sectional view of one of the legs in the region of the foot rest.

Fig. 5 is an enlarged fragmentary sectional view of the seat through one of the dovetail sockets showing the manner of attaching a leg.

Fig. 6 is a bottom face view of the seat.

Fig. 7 is an enlarged fragmentary bottom face view of the seat to plainly show the construction of a dovetail socket.

Fig. 8 is a section on the line 8—8 of Fig. 5 with the leg detached.

In carrying out my invention as herein embodied 10 represents a stool seat having several dovetail sockets 11 formed in the bottom or underneath face thereof. Said sockets are contained wholly inside of the rim of the seat and are arranged in radial lines. Each dovetail socket includes a dovetail recess or cavity 12 closed at its outer end and having beveled side walls but opening to the underneath face of the seat and also opening at its inner end to the component or associated ante-chamber 13. This ante-chamber has straight side walls and is as wide as the widest part of the dovetail recess or cavity portion of the socket, as indicated by the dotted lines in Figs. 6 and 7 and plainly shown in Fig. 8. The ante-chamber is open to the underneath face of the stool seat the same as the dovetail recess or cavity and it is to be noted that the dovetail socket, as a whole is of less depth than the thickness of the seat, Figs. 5 and 8.

Each leg 14 has a dovetail tenon 15 formed on its upper end at the proper pitch to give the desired spread to the legs such as or similar to that illustrated in Fig. 1. The dovetail tenon is of less width than the leg to provide substantial shoulders 16 for a purpose to be presently described. A suitable adhesive, such as glue, is placed in each dovetail socket and the dovetail tenon of a leg is then inserted in the ante-chamber of a dovetail socket and finally the leg is forced outward to cause the tenon to enter the recess or cavity portion of the socket. The shoulders on each side of the tenon rest against the underneath face of the seat to support the latter and because of the rather long formation of the tenon and its close, snug or forced fit in the socket such leg cannot rock or wiggle and become loose which might cause it to break.

Diametrically opposite or radially disposed 45 pairs of legs are tied or braced by stretchers 17, one above the other. Each end of each stretcher has a dovetail tenon 18 formed thereon in proper angular position to fit the dovetail notches 19 running laterally from one face to the other of 50 the leg. During the assembling operations glue is applied so that the stretchers will be retained in place and because of the shoulders 20 above and below the tenons the legs are further held against wiggling and the dovetail formation of 55 the tenons positively prevents spreading of the

legs which is not the case with endwise disposed nails, screws, dowels and the like.

A foot rest 21 has its ends glued in notches 22 in adjacent legs or those disposed in a plane intersecting a chord of the seat.

From the foregoing it will be apparent that I have provided a stool that can be manufactured expeditiously in large quantities without the use of separate fastening devices, requiring only wood and a suitable adhesive, and thereby reducing the cost of material and labor.

Of course I do not wish to be limited to the exact details of construction herein shown and described as these may be varied within the scope of the appended claim without departing from the spirit of my invention.

Having described my invention, what I claim as new and useful is:

A stool comprising a seat having four radially arranged dovetail sockets each comprising a dovetail recess and a communicating ante-chamber and opening only to the underneath surface of the seat, said ante-chamber being as wide as the widest part of the dovetail recess and of the same depth, legs having dovetail tenons on their upper ends adapted to enter the dovetail recesses through the ante-chamber and glued in place, stretchers, and dovetail tenons on each end of each stretcher and glued in dovetail notches in diametrically opposite legs with one stretcher overlying the other.
